UNITED STATES PATENT OFFICE.

DUDLEY B. BULLARD AND JOHN J. MINITER, OF BRIDGEPORT, CONNECTICUT.

INCANDESCENT-LAMP SOCKET.

No. 826,225.

Specification of Letters Patent. Patented July 17, 1906.

Application filed October 13, 1904. Serial No. 228,818.

To all whom it may concern:

Be it known that we, DUDLEY B. BULLARD and JOHN J. MINITER, citizens of the United States, and residents of Bridgeport, in the county of Fairfield and State of Connecticut, have invented certain new and useful Improvements in Incandescent-Lamp Sockets, of which the following is a specification.

Our invention relates to new and useful improvements in electric lamps, and more particularly to the "socket," so called, for incandescent lights.

It is the object of our invention to produce an improved construction of socket whereby a saving of electrical power will be accomplished.

In factories and wherever a large number of lights are used it is obvious that they are frequently left burning unnecessarily during dark days, which is usually due to carelessness or neglect on the part of the user who fails to turn them off when through using. This unnecessary consumption of power is of great importance to concerns using many lights, and it is with a view of saving this waste of power that we have designed our new lamp-socket.

The construction and operation of our novel lamp-socket, as will be more fully explained, is such as to permit of the current being cut out from a distant point—as, for instance, from the power-room or station where the electricity is generated—in a way to require the individual manipulation of each lamp in order to be relighted. The lamps in the circuit may again be lighted by operating a button constructed in a way to be turned off by an instantaneous breaking of the circuit, which may be effected by quickly opening and closing the switch, as hereinafter described. The construction of our improvement is such as to permit of its application to many of the commercial forms of cases now found upon the market.

With the above and other minor objects in view our invention resides and consists in the novel construction and combination of parts shown upon the accompanying sheet of drawings, forming a part of this specification, and upon which similar characters of reference denote like or corresponding parts throughout the several figures, and of which—

Figure 1 shows a central vertical longitudinal section through our improved lamp-

socket complete and showing adjacent thereto a detached sectional view of a lamp such as may be employed in connection therewith. Fig. 2 is a plan view of the socket, the top or cap-piece of the casing being removed. Fig. 3 is a detail plan view of a limb of the electromagnet shown in the preceding views. Fig. 4 is a detail sectional view of the spool upon which the wire coils of the magnet are wound and the magnet-core and limb. Fig. 5 is a detail sectional view of the magnet-core and limb shown in Fig. 4.

Referring in detail to the characters of reference marked upon the drawings, A represents a suitable casing, B the cap or cover therefor, both of which are of substantially the usual construction having an opening C therethrough for the operation of the armature, the whole being adapted for the attachment to a bracket in the usual way by means of a screw, as indicated by D. Within this casing is arranged an electromagnet comprising a central core E, having a limb I, and a spool upon which the usual wire coils G are wound. This spool consists of a barrel F, adapted to fit upon the core, and contains 80 heads F' at either end, all of which spool is formed of insulating material.

It will be obvious from the foregoing that the wire may be first wound upon the spool and then placed upon the core, after which the limb I can be attached by means of the screw H. The limb I extends outward from the core, then up and turned over the top head F' to form an electrical contact at J.

A fibrous or other insulating piece is placed beneath the limb I and intermediate of it and the threaded holder K', which is attached thereto by means of the screw M. This holder K' serves to receive the lamp L in the usual way by means of the latter being screwed therein. When inserted as above, the respective wires of the lamp engage with the screws H and holder K', the former being connected with the core and limb, while the latter, through the screw M and its wires O, 100 is connected with the coil G.

The line-wires P and P' are secured to the screws Q' and R, respectively, the former being connected with the coil, while the latter is connected with the bracket S, to which the armature T is pivotally connected. The core of the magnet is provided with a spring-actuated pin U, that engages the under side of the

armature in a way to normally hold it up off of the contact end J of the limb, as shown in dotted lines, at such times as when the circuit is broken, but to allow its forming an electrical contact with said limb when so placed by an attendant and by reason of the influence of the magnet, which obviously becomes charged when armature is placed in said engagement. The under side of the armature adjacent to the top end of the core is provided with a thin strip U' of insulating material, which overcomes the magnetic attraction of the armature by the residual magnetism of the electromagnet, permitting the spring-pin U to force the armature up when the magnet is not charged, thereby breaking the electrical contact at point J.

When our lamps are set up in circuit, they become operative when the armature is manipulated by an attendant and brought down into engagement with the limb, which completes the electrical circuit through the armature charging the magnet in a way to hold the armature in contact at J and continuing such engagement and operating until such time as when the attendant disconnects said armature to extinguish the light or at such other times as when the engineer or attendant at the main station operates the switch to break the circuit, it being of course understood that the moment the current is cut out the magnet in the socket becomes ineffective, permitting the spring-pin U in the core of the magnet to exert its influence and throw the lever up into the position indicated in dotted lines, thereby breaking the circuit, where it remains until again adjusted by an attendant.

Having thus described our invention, what we claim, and desire to secure by Letters Patent, is—

1. In an electric-lamp socket, the combination with an electrohorseshoe-magnet, of binding-posts on the magnet, an armature pivotally connected with one of said posts and adapted to simultaneously engage the two limbs of the magnet, a lamp-socket attached to the magnet within the circuit, and a spring intermediate of said limbs to engage the armature for automatically disconnecting the same from the magnet when the electrical circuit is cut out.

2. In an electric-lamp socket, the combination with a magnet provided with connecting-posts for field-wires and a connected

lamp-holder, of an armature to connect one of said posts with the magnet and bearing operating means, and a spring within the magnet to engage the intermediate portion of the armature whereby its connection with the magnet will be automatically broken when the circuit is cut out.

3. In an electric-lamp socket, the combination with a horseshoe-electromagnet provided with connecting-posts, of an armature extending across both points of the magnet, a lamp-socket secured to the magnet within the circuit, a spring within one limb of the magnet for automatically operating said armature to disconnect the same from the magnet when the circuit through the socket is cut out, and means for operating the armature against the action of its spring.

4. In an electric-lamp socket, the combination with an electromagnet having connecting-posts for line-wires, of a lamp-holder attached to and electrically connected to the magnet, an armature pivotally attached to one of the posts and adapted to engage the magnet, a spring and plug within the core of the magnet adapted to disconnect the armature when the circuit through the socket is broken.

5. In an electric-lamp socket, the combination with a magnet comprising a core and a limb, of an armature adapted to normally contact with both the core and limb, a line-wire binding-post for each the armature and magnet, a holder for a lamp attached to the magnet, an inclosed spring within the magnet-core for automatically operating the armature to disconnect it from the limb when the electric current is cut out of the socket.

6. An electric-lamp socket comprising a magnet containing a core having a limb, binding-posts upon the magnet, an armature to engage said limb and connected with one of said posts and bearing an extension for operating said armature, a spring within the core to disconnect the armature from the limb when the circuit is cut out, and a lamp-holder attached to said magnet.

Signed at Bridgeport, in the county of Fairfield and State of Connecticut, this 11th day of October, A. D. 1904.

DUDLEY B. BULLARD.
JOHN J. MINITER.
